UNITED STATES PATENT OFFICE

ROBERT W. NICHOLLS, OF PALISADE, NEW JERSEY, ASSIGNOR, BY MESNE ASSIGNMENTS, TO ANDREW J. SORBELLO, OF NEW YORK, N. Y.

PIPE

Application filed September 15, 1924, Serial No. 737,668. Renewed February 12, 1930.

This invention relates to tobacco pipes.

Among the objects of the invention are to improve the construction of such pipes; to provide for keeping them cleaner and sweeter; to adapt them to be readily cleaned and aired; to permit the optional use of means for eliminating nicotine during the operation of the pipe; to construct the pipe in such a manner as to permit the various parts to be formed of a wide range of materials and to be stamped, molded, cut or otherwise shaped; and, generally, to provide a novel construction and arrangement of pipe and to improve the smoking qualities thereof.

15 The invention resides in the construction, combination and arrangement of parts and in the details of construction as hereinafter described and claimed, it being understood that many changes in the construction and arrangement of parts and in the details of the pipe may be made within the scope of the claims and as indicated by the variations between the different claims, without departing from the spirit or the scope of the invention.

In the accompanying drawing forming part of this specification,

Figure 1 is a side elevation of one of the forms of the pipe, the nicotine eliminator being absent;

Figure 2 is a bottom or inside view of the upper half of the stem showing the longitudinal smoke channel communicating at one end with the bowl-receiving-opening;

35 Figure 3 is a bottom or outside view of the lower half of the stem;

Figure 4 is a transverse section of the bowl looking toward the stem and showing the bowl fitted into the upper stem member and the clip for holding the bowl and the two stem members in assembled relation;

Figure 5 is a sectional view of part of the construction shown in Fig. 1 and with a sheet of nicotine eliminating material shown in position;

Figure 6 is a top plan view of the clip or clamping device as shown in Figs. 1, 4 and 5;

50 Figure 7 is a view of a modified form of

the clamping device adapted to be shaped from an endless ring of material;

Figures 8 and 9 are views similar to Figs. 2 and 3 showing a modified construction in which one of the members of the stem is provided with a rib and the other with a corresponding groove to receive the rib;

Figure 10 is a sectional view on the line 10-10 of Figs. 8 and 9;

Figure 11 is a view similar to Fig. 4 showing a modified construction of the pipe;

Figure 12 is a longitudinal section showing a modified construction in which part of the stem is made integral with the bowl;

Figure 13 is a top plan view of the construction shown in Fig. 12.

Like reference numerals indicate corresponding parts in the different figures of the drawing.

Referring to the construction illustrated in Figs. 1, 2, 3, 4, 5 and 6, reference letter A indicates the bowl; B the stem formed of two separable elements; and C the clip by which the bowl and stem elements are held assembled.

The upper element 2 of the stem B, as illustrated in Figs. 2, 4 and 5, is formed in its under or inside face with a smoke channel 1 which extends from the mouth end of the stem to the bowl end thereof. The stem element 2, preferably, is thickened as it approaches the bowl and is then formed with a slight downward bevel 3, best shown in Figs. 1 and 5, on which the bowl A rests. The bowl receiving portion 3 of the element 2 is provided with a circular opening 4 into which the smoke channel 1 opens.

The bowl A as shown in Fig. 5 is provided with a tobacco receptacle 5 which extends through the bowl from top to bottom, and on its lower end the bowl is provided with an annular flange 6 which is shaped to fit into the opening 4 in the stem element 2.

The lower element 7 of the stem B preferably is flat on its upper surface and serves, functionally, to close the lower end of the smoke channel 1 when the stem is assembled.

On its lower face, as best shown in Figs. 3 and 5, the stem element 7 is formed with a circular groove 8 and a short sharp bevel 9,

75

80

85

90

100

Fig. 5, which extends between the shoulders 10 and 11 in Fig. 3 and serves to provide a beveled guide channel by which the lower ends 12 of the spring clip C are guided into their position within the circular groove 8.

The clip C preferably is formed with the circular portion 14 which fits into a groove 15 in the bowl A, the two ends of the ring 14 being held in assembled position by the link 17.

In assembling the construction illustrated in Figs. 1 to 6, the upper element 2 is inserted over the arms 12 of the clip and the hole 4 is fitted over the flange 6 of the bowl. Then the lower stem element 7 is placed flat against the element 2, with the outwardly bent ends 12 of the arms 12, just resting within the ends of the beveled channel 9 in Fig. 3. In this position, the stem element 7 projects beyond or overlaps the element 1, and by now pushing the element 7 in the direction of the bowl A the spring arms 12 slide up the beveled face 9 and snap into the circular groove 8, thus holding the three elements of the pipe in assembled position.

The construction described permits the two elements of the stem to be rotated or swung in opposite directions without disassembling the pipe and by this simple action, the smoke channel of the element 2 is exposed for cleaning. The three parts of the pipe can of course be easily disassembled for thorough airing and cleaning.

I prefer to shape the stem elements 2 and 7 so that, as shown in Fig. 1, they tend normally to spring slightly apart at the mouth end of the stem as indicated at 18. This enables the smoker to use the pipe either with the two stem elements pinched tightly together for a hot smoke, or to procure a cooler smoke by drawing in a regulatable amount of air through the ends of the stem elements which are nearest the mouth.

The construction described also permits the smoker if desired to place a sheet of paper indicated by 19 between the upper and lower stem elements. Any kind of paper can be used for this purpose, as any projecting edges of the paper can be readily torn away. The use of the paper 19 serves to provide what might be called a roughly absorbent bottom for both the bowl of the pipe and the smoke channel 1 throughout its length, and it is found in practice that the nicotine or tobacco oil is absorbed or eliminated from the smoke by the nicotine eliminator 19.

It is found in practice that when the paper 19 is used, it tends to assume a wavy effect along the smoke channel as shown in Fig. 9 due to the action of the heat and moisture.

In Fig. 7, I have illustrated a modified arrangement of the clip C using an endless ring of wire in which 14^a is a ring fitted permanently in the groove 15, and 14^b are twisted portions forming downwardly, inwardly and upwardly bent spring arms 14^c which serve

the same function as the arms 12 in Fig. 5. The remaining construction of the pipe is the same as illustrated in Figs. 1 to 5 and when the clamping device of Fig. 7 is used in place of that shown in Fig. 1, the parts are assembled in the same manner as previously described.

The modified construction illustrated in Figs. 8, 9, 10 and 11 comprises a bowl A' having a closed lower end 21 and a threaded lower portion 22 which is designed to engage an opening 4^a in the upper stem element 2^a and also to engage the threads of an opening 4^b in the lower stem element 7^a.

In this construction, I prefer to employ, as a means of preventing any leakage of air and of holding the stem elements against relative rotation, a rib 24 which, as shown in Fig. 10, fits into corresponding groove 25 in the upper stem element 2^a, but this rib and groove may be omitted if desired. The rib 24 starts on one side of the mouth end of the pipe and extends longitudinally of the stem element around the bowl and then back along the other side of the stem element of the mouth end.

At its lower end the bowl is provided with one or more elongated smoke slots 26 designed to be registered with the smoke channel 1^a in the stem element B.

In assembling the structure of Figs. 8 to 11, the two stem elements are fitted together with the rib 24 engaging the groove 25. The bowl is then screwed down through the bowl openings in the two stem elements, thus serving to hold the three elements of the pipe in assembled position.

The construction modified, illustrated in Figs. 12 and 13, is adapted to be formed of any suitable metal or other material.

I prefer to form the upper stem element 2^a integral with the bowl A^a.

Clamped or otherwise suitably secured to the mouth ends of the stem elements 2^a and 7^a are lips 30 and 31 formed of any suitable composition or other material.

The upper stem element 2^a preferably is reinforced by three longitudinally extending, integral ribs 32 which at their bowl ends are continued upwardly to form three cooling flanges 32^a.

The interior of the bowl A^a is lined with a cylinder of any suitable heat insulating material or compound indicated by 33 and within that is a metal cylinder 34 which forms the tobacco receptacle.

The upper and lower stem elements in Figs. 12 and 13 are held in assembled relation by means of a metal clip 35, the ends of which engage the outer edges of the upper stem element 2^a and the lower portion of which is arranged to slide on the tapering ribs 36 of the lower stem element 7^a. By sliding the clip 35 toward the bowl A as far as it can

slide up the tapering ribs, the two parts of the pipe are clampel tightly together.

In all of the forms of the invention as illustrated, I prefer to equip the bowl with heat dissipating flanges indicated by 40 in Figs. 1 and 4, by 40^a in Fig. 11 and by 40^b in Fig. 13, but these flanges may be omitted if desired.

The bowl in Fig. 1 preferably is made of pipe wood and the stem sections 2 and 7 of 10 any suitable pipe composition or other material.

The improved pipe structure as a whole presents a novel and pleasing appearance. Different kinds of bowls can be readily used 15 with a single set of the stem elements. The pipe provides a cool, sweet smoke and is readily cleanable.

Since certain changes may be made in the above article and different embodiments of 20 the invention could be made without departing from the scope thereof, it is intended that all matter contained in the above description or shown in the accompanying drawing shall be interpreted as illustrative and not in a 25 limiting sense.

It is also to be understood that the following claims are intended to cover all of the generic and specific features of the invention herein described, and all statements of the 30 scope of the invention which, as a matter of language, might be said to fall therebetween.

Having described my invention what I claim as new and desire to secure by Letters Patent is:

35 1. A pipe having a stem formed of two elements, one of them having a smoke channel therein and one of them having a bowl-receiving-opening therein, each separable from the bowl and from each other, a bowl capable of fitting in said opening, and means for holding the bowl and the stem elements assembled, said means comprising a clamp connected with the bowl and embracing the stem elements.

45 2. A pipe having a stem formed in two parts, one of said parts having an opening therein to receive the bowl, and means carried by the bowl and engageable with the lower stem part for holding the stem and the bowl in assembled relation.

50 3. A pipe including an open bottomed bowl and a sectional flat stem upon which the bowl seats, a spring ring encircling the bowl and including an integral offset spring hook portion embracing the stem and holding the stem and bowl together.

55 4. A pipe including a pair of superimposed generally similar stem sections divided from end to end and cooperatively defining a smoke channel, the upper of said sections having an opening therein, and a removable bowl piece communicating with said channel through said opening, and means carried by the removable bowl piece for securing all 60 three of said parts together.

5. A pipe including a pair of superimposed generally similar stem sections divided from end to end and cooperatively defining a smoke channel, the upper of said sections having an opening therein, and a removable bowl piece communicating with said channel through said opening, and means carried by the removable bowl piece for preventing relative movement of the stem sections. 70

6. A pipe including a pair of superimposed generally similar stem sections divided from end to end and cooperatively defining a smoke channel, the upper of said sections having an opening therein, and a removable bowl piece communicating with said channel through said opening, and means carried by the removable bowl piece and engaging only the lower stem section for holding all of the parts in properly assembled relationship. 75

7. A pipe including a pair of superimposed generally similar stem sections divided from end to end and cooperatively defining a smoke channel, the upper of said sections having an opening therein, and a removable bowl piece communicating with said channel through said opening, and means carried by the removable bowl piece and slidably engaged with the lower stem section for holding the bowl and the stem sections in proper assembled relationship. 80

8. A pipe including a pair of superimposed generally similar stem sections divided from end to end and cooperatively defining a smoke channel, the upper of said sections having an opening therein, and a removable bowl piece communicating with said channel through said opening, and means carried by the removable bowl piece for securing all three of said parts together, said means comprising a spring clip. 85

In testimony whereof I affix my signature.

ROBERT W. NICHOLLS.
